UNITED STATES PATENT OFFICE.

RALPH WILLOUGHBY OSBORNE, OF TORONTO, ONTARIO, CANADA.

RADIO FREQUENCY TRANSFORMER.

Application filed December 27, 1927. Serial No. 242,671.

My invention relates to improved types of radio frequency transformers for use as input and output transformers of radio frequency amplifiers, radio frequency genera-

5 tors and the like, and for interstage transformers or couplers in cascade radio frequency amplifiers in radio transmitting and receiving apparatus, or for the transformation of any high frequency energy where 10 electro-static coupling between the windings of the transformer is detrimental to the efficiency of transformation.

To those familiar with the art, it is well known that the electro-motive forces of electro-static and electro-magnetic induction 15 cause currents to flow respectively which are in phase opposition to each other and that in radio-frequency transformers, a very small electro-static capacity between the 20 windings may cause an appreciable transfer of energy from the primary winding to the secondary winding by electro-static induction in opposition to the energy transferred by electro-magnetic induction, thus reducing 25 the efficiency of transformation, unless in the designing of the transformer care is taken to so arrange the windings that the effect of electro-static induction between windings is minimized.

30 The object of my invention is to provide a type of radio frequency transformer wherein the effect of electro-static induction between windings, as opposed to electro-magnetic induction, is zero.

35 To attain this object I provide a radio frequency transformer with primary and secondary windings so arranged and inter-related that when energized, the electro-static flux emanating from either winding 40 induces in the other winding equal and opposite components of electro-motive forces whose resultant difference of potential between the extremities of the said other winding is zero, while the electro-magnetic flux emanating from either winding induces in 45 the other winding electro-motive forces which are cumulative. The attainment of this object as above stated is made possible due to the fact that when an object such as 50 a wire is electrified, the electro-static flux emanates from the wire radially and is a function of the voltage at which the wire is charged, while the electro-magnetic flux encircles the wire and is a function of the current flowing in or along the wire; wherein

the difference in the behaviour of the two forms of flux makes it possible to eliminate the effects of one without interfering with the effects of the other.

In order to understand my invention more 60 fully reference may be had to the following description and accompanying drawings illustrating a form of my invention, in which Figs. 1, 1^a, 1^b and 2, 2^a are end and side elevations respectively, Figs. 3 and 4 two 65 types of radio receiving circuits illustrating more clearly how my invention may be adapted to function in various types of circuits and in different parts of a given type of circuit.

70 Referring to the drawings it will be noted that in Figs. 1, 1^a and 1^b I have shown a radio frequency transformer having a primary winding 11 in two halves 1 and 2 as indicated, respectively, by the lightly shaded 75 and heavily shaded strands, wound about an even number of spokes in a radial plane at right angles to the axis of a secondary winding 5 wound in two halves 3 and 4 in cylindrical form. In winding the primary 80 winding 11 it will be noted that the darkly shaded strand 2 is started at terminal 6 and wound in a counterclock-wise direction and woven in and out about the spokes for a half turn to point 7, then the lightly shaded 85 strand 1 is started at terminal 6 and wound in a clock-wise direction and wound in and out about the spokes until it crosses strand 2 at point 7; then strand 2 is continued to point 8 and strand 1 is continued until it 90 crosses strand 2 at point 8, the process continuing in this order until the winding is completed at terminals 9 and 10. Upon close examination it will be seen that strands 1 and 2 occupy similar positions for equal 95 distances throughout their length with reference to the secondary winding 5 or other objects in their vicinity. When the primary winding 11 is energized strands 1 and 2 assume, respectively, equal and opposite potentials with reference to the neutral point 100 6, and the electro-static flux emanating from strand 1 will be equal to, and of opposite polarity to that emanating from strand 2, so that equal components of electro-static 105 flux of opposite polarity will radiate from the primary winding 11 to the secondary winding 5 and the resultant potential induced thereby will be zero; while the electro-magnetic flux due to current flowing in 110

the strands, and which encircles the strands will be cumulative because the current flowing in adjacent turns of strands 1 and 2 is in the same relative direction. The above 5 described condition of electro-static induction between primary and secondary windings inducing zero potential in the secondary winding, is the same regardless of the relative positions of the two windings, although 10 electro-magnetic inductive effects will be reduced as the windings are separated. While Fig. 1^a shows the primary winding 11 centrally located with reference to the secondary winding 5, it is advantageous for some purposes to locate the primary winding at one 15 end of the secondary winding as shown at 11' in Fig. 1^b.

If conditions are the reverse of the above 20 description, that is to say if the cylindrical winding 5 is the primary winding and is energized the electro-static flux emanating from the cylindrical winding 5 will impinge equally upon strands 1 and 2 of the other winding 11 inducing equal potentials of the 25 same polarity in strands 1 and 2, thus causing no difference of potential between the terminals 9 and 10; while the electro-magnetic flux encircling the turns of the cylindrical winding 5 will also encircle strands 30 1 and 2 of the other winding thus inducing potentials which are cumulative and result in a difference of potential between terminals 9 and 10 of winding 11. A transformer constructed in this form is used as an 35 interstage transformer as indicated at 22 in Fig. 3 of the drawings.

As will be evident when further description discloses the various adaptations of my 40 transformer, it may be constructed in various forms without departing from the basic principle employed to attain the object of my invention.

When the primary winding 11 is in the 45 form already described and is centrally located with reference to the secondary winding 5 as indicated in Fig. 1^a, the secondary winding 5 is divided into two halves 3 and 4 the terminals 12 and 13 being joined together to form a neutral point. When the 50 primary winding is placed at the end of the secondary winding as indicated at 11' in Fig. 1^b, the secondary winding 5' is usually wound in a single section having no neutral point. A transformer constructed in this form is 55 used as an output transformer as indicated at 29 in Fig. 3 and at 49 in Fig. 4.

In Figs. 2 and 2^a the primary winding is 60 constructed of a single conductor wound about an odd number of spokes and centrally located with reference to the secondary winding 5" in Fig. 2^a. In this form it will be similar in appearance to the transformer as indicated in Fig. 1^a, the single conductor primary winding being located in the same 65 relative position as the primary winding 11

previously described. The terminals 12' and 13' of the two halves 3' and 4' of the secondary winding 5" are joined together to form a neutral point. The primary winding 11" being equidistant from the several turns respectively of each half 3' and 4' of the secondary winding 5" so that when the primary winding is energized, the electro-static flux emanating from the primary winding will be impinged equally and at the same 70 polarity on the several turns of each half 3' and 4' respectively of the secondary winding 5", causing no difference of potential at the terminals 14' and 15' of the secondary winding 5", while the electro-magnetic flux set 80 up around the primary winding will encircle the two halves 3' and 4' of the secondary winding 5" inducing potentials which are cumulative. A transformer constructed in this form is used as an input transformer as 85 indicated at 18 in Fig. 3 of the drawings. If in this type of transformer conditions are reversed, that is to say, if the cylindrical winding 5" is used as a primary winding and the single conductor winding wound about the odd number of spokes centrally 90 located with reference to the cylindrical winding 5", is the secondary winding, it may be used as an output transformer as indicated at 29 in Fig. 3 and at 49 in Fig. 4 95 of the drawings.

Fig. 3 of the drawing, is a diagrammatic view of a radio receiving apparatus employing a cascade radio frequency amplifier of the balanced or push-pull type in which 16 is the antennæ, 18 is the input radio frequency transformer of which 17 is the primary winding, comprising a single conductor wound upon an odd number of radial spokes and centrally located with reference 100 to the secondary winding wound in cylindrical form in two halves 19 and 20, said secondary winding having its neutral point 21 connected to ground by means of ground wire 42, the extremities of said secondary 105 winding being connected respectively to the grids of the amplifying tubes 37 and 38. 22 is an interstage transformer of the form indicated in Figs. 1 and 1^a in which extremities 23 and 24 correspond respectively 110 to terminals 9 and 10 in Fig. 1 and are connected respectively in the plate circuits of amplifying tubes 37 and 38, the neutral point 25 corresponding to terminal 6 in Fig. 1 being connected to a source of battery supply B by means of wire 43. 27 and 28 are the two halves of the secondary winding corresponding respectively to the two halves 3 and 4, of the secondary winding 5 in Fig. 1^a, the extremities of which are connected respectively to the grids of the amplifying tubes 39 and 40, 26 is the neutral point formed by joining terminals 12 and 13 in Fig. 1^a, connected to ground by means of wire 44 and secondary winding 35 of audio 125 130

frequency transformer 34. 29 is the output transformer in which 30 and 31 of the primary winding correspond respectively to terminals 9 and 10 in Fig. 1 and are connected respectively in the plate circuits of the amplifying tubes 39 and 40, the neutral point 32 corresponding to terminal 6 in Fig. 1 being connected to a source of battery supply B through wire 45 and reproducing device 46, and 33 the secondary winding wound in a single section and having the primary winding located at one end as indicated at 11' in Fig. 1^b. Secondary winding 33 delivers the amplified radio frequency energy to the detector tube 41. In order to illustrate further advantages to be gained by the use of my radio frequency transformer, I have shown how the signals may be delivered from the detector 41 to the primary winding 36 of the audio frequency transformer 34, thence from the secondary winding 35 to the neutral point 26 of the secondary winding of the radio frequency transformer 22 by means of wire 44, dividing at the neutral point 26 through each half 27 and 28 of the secondary winding of the radio frequency transformer 22 to the grids of the amplifying tubes 39 and 40, and how the amplified audio frequency energy is delivered from the plates of amplifying tubes 39 and 40 through the two halves of the primary winding of radio frequency transformer 29 to neutral point 32 thence by means of wire 45 to the reproducing device 46. The amplifying tubes 39 and 40 thus amplify the radio frequency and audio frequency energy simultaneously without interference between the two frequencies because the electrodes of the tubes 39 and 40 are respectively at opposite polarities with reference to the radio frequency energy, while they are at the same polarity with reference to the audio frequency energy.

I have shown how my invention may be adapted to the balanced or push-pull type of radio-frequency amplifier. When used in this manner it operates in a more satisfactory manner than the conventional types of radio frequency transformers heretofore in use, because of its higher efficiency, less tendency to go into self oscillation and comparative freedom from outside interference and static. My invention may also be adapted to the one tube per stage type of amplifier as indicated in Fig. 4 of the drawings in which 47 is the antennæ, 48 a conventional type of input transformer delivering energy to the grid circuit of amplifying tube 54, 49 is an adaptation of my transformer as an output transformer with one extremity 50 of the primary winding connected in the plate circuit of the amplifying tube 54 while the other extremity 51 is connected to the grid 65 of the tube through balancing condenser 57.

The secondary winding 53 delivers the amplified radio frequency energy to the detector tube 56.

While I have shown and described one embodiment of my invention and various adaptations thereof, it will be understood that various modifications in form and construction of its component parts may be made without departing from the spirit and scope of the appended claims.

What I claim is:

1. A radio-frequency transformer comprising a winding wound in cylindrical form and a winding wound on a support in a radial plane fixed at an angle with the axis of the said winding wound in cylindrical form and having a neutral point, the successive turns on either side of the said neutral point being transposed at intervals so that when energized all parts of the said winding wound on a support in a radial plane that are at equal and opposite potentials are equidistant from the winding wound in cylindrical form.

2. A radio-frequency transformer comprising a winding wound in cylindrical form and having a neutral point and a winding wound on a support in a radial plane fixed at an angle with the axis of, and coincident with the neutral zone of the said winding wound in cylindrical form, said winding wound on a radial support having a neutral point, the successive turns on either side of the neutral point being transposed at intervals so that when energized all parts of each winding that are at equal and opposite potentials are equi-distant from the other winding.

3. A radio-frequency transformer comprising a winding wound in cylindrical form and having a neutral point connected to a terminal, a number of radial spokes set in a radial plane at right angles to the axis of, and coincident with the neutral zone of the said winding wound in cylindrical form and a winding wound in spider-web form about the said radial spokes.

4. A radio-frequency transformer comprising a winding wound in cylindrical form, an even number of radial spokes set in a radial plane at right angles to the axis of the said winding wound in cylindrical form, a winding wound in spider-web form about the said radial spokes, said winding being in two halves and having a neutral point, the individual turns of each half being wound alternately, one in a clock-wise and the other in a counter-clock-wise direction, crossing and recrossing between the spokes, the said two halves of the winding being joined in series relation, the junction being the neutral point which is connected to a terminal.

5. A radio-frequency transformer comprising a winding wound in cylindrical form

and having a neutral point connected to a terminal, an even number of radial spokes set in a radial plane at right angles to the axis of, and coincident with the neutral zone 5 of the said winding wound in cylindrical form, a winding wound in spider-web form about the said radial spokes, said winding being in two halves and having a neutral point, the individual turns of each half being wound alternately, one in a clock-wise and the other in a counter-clock-wise direction, crossing and recrossing between the spokes, the said two halves of the winding being joined in series relation, the junction 10 being the neutral point which is connected to a terminal.

6. A radio-frequency transformer comprising a winding having a neutral point and another winding in electro-magnetic inductive relation thereto, each successive turn 15 on either side of the neutral point of said winding having a neutral point so positioned in equidistant relation to each successive turn of the said other winding in electro-magnetic inductive relation thereto, that when the

said transformer is energized the electrostatic flux emanating from either winding induces in the other winding an even distribution of electrostatic charges causing no resultant difference of potential between the 30 extremities of the said other winding, while the electro-magnetic flux emanating from either winding induces in the other winding electromotive forces which are cumulative.

7. A radio-frequency transformer comprising 35 a winding wound in cylindrical form and having a neutral point, and a winding wound on a support in a radial plane fixed at an angle with the axis of, and coincident with the neutral zone of the said winding 40 wound in cylindrical form so that when energized all parts of the said winding wound in cylindrical form that are at equal and opposite potentials are equidistant from the winding wound on a support in a radial 45 plane.

In testimony whereof I affix my signature this twenty-first day of December at the city of Toronto.

RALPH WILLOUGHBY OSBORNE.
